UNITED STATES PATENT OFFICE.

LOUIS MEARS FORD, OF CHICAGO, ILLINOIS; CONTINENTAL AND COMMERCIAL TRUST AND SAVINGS BANK, ADMINISTRATOR OF SAID LOUIS MEARS FORD, DECEASED, ASSIGNOR TO FORD ROOFING PRODUCTS COMPANY, OF CHICAGO, ILLINOIS, A CORPORATION OF ILLINOIS.

ROOFING PRODUCT.

Application filed September 18, 1921. Serial No. 501,085.

To all whom it may concern:

Be it known that I, LOUIS MEARS FORD, a citizen of the United States, and a resident of Chicago, county of Cook, and State of Illinois, have invented a certain new, useful, and Improved Roofing Product, of which the following is a specification.

My invention relates generally to improvements in roofing products, or materials, but 10 has especial reference to improvements in so-called composition roofing.

The general object of my invention is to provide a roofing material or product whereby with a truly individual shingle effect can be secured.

It is also an object of my invention to provide a roofing material or product that can be so applied as to eliminate entirely all flapping of the material and hence to overcome the resulting noise, nuisance, and roof leakage.

Again it is an object of my invention to provide a roofing material or product in which the individual shingle effect can be secured with much less material than is required when using roofing products or shingles heretofore devised for that purpose.

I also aim to produce roofing material having the characteristics of great coverage, 30 individual shingle effect, and permanence and leak-proofness, and which at the same time can be applied quickly and easily by any one with even little skill.

My invention consists of a piece of roofing material of the form, composition, design and co-relation of design and form or shape whereby the above named objects, together with others that will appear hereinafter, are attainable; and my invention will be more 40 readily understood by reference to the accompanying drawings, which illustrate what I consider, at the present time, to be the preferred embodiment thereof.

In said drawings:

Fig. 1 is a face view of a piece of roofing material embodying my invention.

Fig. 2 is an enlarged fragmentary cross-sectional view thereof, substantially on the line 2-2 of Fig. 1.

Fig. 3 is an enlarged fragmentary cross 50 sectional view, substantially on the line 3-3 of Fig. 1.

Fig. 4 is a face view of a piece of roofing material of still another form embodying my invention.

Fig. 5 is an enlarged fragmentary cross-sectional view substantially on the line 5-5 of Fig. 4.

Fig. 6 is a vertical sectional view of the sheet shown in Fig. 4, after it has been 60 folded.

Fig. 7 is a detail sectional view, illustrating the application of the roofing material to a roof.

Fig. 8 is a plan view of the roofing as applied in Fig. 7, illustrating contiguous sheets.

Fig. 9 is an enlarged detail view substantially on the line 9-9 of Fig. 8.

I shall first describe that form of my invention illustrated in Figs. 1 to 5, inclusive.

Therein 1, is a sheet or piece of composition roofing of the form such as I prefer to use. I find that a sheet 32 inches wide and say five feet in length, one which may be 75 conveniently utilized.

As here shown, it is composed of a layer of felt paper 2 which has been saturated with asphalt or similar suitable material and to the upper and lower faces thereof there is applied a heavy coating of asphalt which is indicated by the reference characters 3 and 4, respectively. The bottom of the sheet is provided with a thin coating 5 of some anti-friction material such for instance as mica. On the outer face of the asphalt coating 3, there is applied a surfacing material 6 of crushed rock, slate, or similar material, in such manner as to provide a design on the face of the sheet, which are here shown as a plurality of rectangular areas 7 (see Figs. 2 and 3). A number of rectangular transversely extending grooves or recesses 8 and a number of offset grooves or recesses 9 and 10, disposed longitudinally 80 of the sheet, are provided. The surfacing material is brought in such contiguity to the upper and lower edges 11 and 12, respec-

tively, as to form transverse marginal portions 13 and 14, respectively, and to the side edge 15 as to form the marginal depression 16, the purpose of which will appear.

5 The asphalt 3 being black and by providing a colored surfacing 6, such for example, as red, a very forceful and bold contrast is caused that accentuates the size of the grooves or depressions and brings out the 10 individual appearance of the shingles.

The transverse grooves 8 are provided for another purpose as are the marginal depressions 13 and 14, all of which, it will be understood, are barren of the crushed rock or slate surfacing material.

The sheet 1 is to be folded transversely along lines coincident with the margins of the grooves 8 and the marginal depressions 13 and 14 at which points it can be folded without danger of cracking. The marginal portion 13 is folded back upon the upper side of the sheet, and the marginal portion 14 under the sheet. The sheet intermediate the marginal portions 13 and 14 is folded so that each barren strip 8 faces downwardly against the upper slate surfaced part of the sheet, thus forming a number of thickened zones comprising three layers of the material, as is well shown in Fig. 6. The sheet in the form shown in Fig. 6 (in so far as the folds are concerned) is the form in which I contemplate shipping the article for use and in this form a number of the sheets can be conveniently packed in a suitable bundle or package.

Referring now to Figs. 7, 8 and 9, for an understanding of the method of applying, 17 represents the roof boards or sheeting to which the roofing material is to be applied, and 18 is the lower edge of the roof. A sheet of the material folded as shown in Fig. 6 is placed upon the roof with the marginal portion 14 downwardly and at the lower edge of the roof, and in this position, 45 fastening devices 19 are driven through the several thicknesses of roofing material, thus firmly affixing the same to the roof. Before driving a fastening device through the marginal portion 14 of a similar sheet of material, such sheet is inserted into the hook-like upper end, formed by the portion 13, and then a fastening device is driven completely through the several layers. It is obvious that it is impossible for rain to 50 drive through any of these joints, because in every instance it is checked by a portion of the material that is folded backwardly.

Fig. 9 shows the manner oflapping the roofing material along the side edges where-in it will be observed that the depressed or marginal portion 16, receives the butt end of the edge portion of the adjacent sheet, thus in a sense, countersinking the same and bringing it more nearly flush with the top surface of the adjacent sheet. In other

words, this construction not only assists in preventing water leakage, but also reduces the visibility of the joint and hence improves its appearance. The several layers are secured together along the lap joint by means of suitably spaced fastening devices 20.

When the roofing sheet or material embodying my invention is applied to the roof it will be seen that it presents to view what appear to be independent shingles, and that these apparently independent shingles terminate in relatively thick butt portions 21, which being composed of several thicknesses of material are visible, no matter what the angle at which the roof is viewed. 75 80

Figs. 4, 5 and 6 illustrate a modification of my invention. The general structural features are the same as those illustrated and described with reference to Figs. 1 to 3, inclusive, and like parts bear like reference characters in order to simplify the description and understanding of this construction. Thus, it appears that the structure shown in Figs. 4 to 6, inclusive, throughout is identical with that shown in Figs. 1 to 3, and is folded in like manner. The one different feature is that the marginal depressed portion 16 is folded back upon the upper surface of the sheet and there is provided a marginal portion 16' upon the opposite edge which is folded backwardly under the sheet, along the dotted line 16''. The sheet may be applied to the roof as already described except that each sheet interlocks with the adjacent sheets, all around inasmuch as all four edges are provided with parts that are folded back to form hook-like portions which are adapted to interlock with the hook-like portions of all contiguous sheets. The portion 16 is further severed at a number of points to form the independent tabs 16^a and 16^b, to facilitate the interlocking of this folded portion of the sheet with the folded portion 16' of the next adjacent sheet. It will be understood that at the time these edge portions are interlocked both the sheets are in the folded overlapped condition illus- 110

trated in Fig. 6. A convenient way of applying this sheet, assuming that one sheet has already been applied to the roof is to turn the entire sheet face down upon the previously laid sheet and then to fold the marginal portion 16' to its initial plane. 120 The whole sheet is then shifted, meantime inserting the tabs 16^a under the folded portion 16 of the previously laid sheet and passing the tab portions 16^b over the said folded sheet portion 16, at which time fastening devices 24 may be applied. After these fastening devices are applied the whole sheet is swung over until its under side is downward against the roof boards or sheeting, in which condition it will be 125 130

found that the two sheets are completely interlocked and the fastening devices protected from the weather.

Some people prefer to lay the roofing 5 lengthwise of the roof instead of from the bottom to the top. For such use the folds will be made longitudinally of the sheet instead of transversely, and where the color bands or the like are to be used they will be 10 applied or formed transversely of the sheet instead of longitudinally. Thus, when such a sheet is applied lengthwise of the roof, it 15 obviously will present the same appearance that the form depicted in the drawings presents when it is applied from the bottom to the top. In other words, there is a mere reversal of the application which is accommodated by a mere reversal of the formation 20 of the folds or plaits and the color bands or surface barren grooves. In the claims, therefore, the terms longitudinal and transverse may be interchanged and the claims should be so broadly construed.

From the foregoing it is apparent that 25 my invention is susceptible of embodiment in a number of different forms, in all of which the desired characteristics of an individual shingle effect and leak-proof and flap proof roof are secured with the use of 30 a minimum amount of material. It should

furthermore be obvious that the roofing product such as I have described can be quickly and easily applied.

I claim:—

1. As an article of manufacture, a roofing 35 material comprising a substantially flexible sheet provided with a plurality of spaced, transversely extending surfaced areas, said areas having adjacent top and bottom edges which define fold lines along which the 40 sheet may be folded to bring a part of one surfaced area into overlapping relation with respect to a part of an adjacent surfaced area.

2. As an article of manufacture, a roofing 45 material comprising a substantially flexible sheet provided with a plurality of rectangular surfaced areas arranged in rows extending in one direction of the sheet, with the areas in one row staggered relatively to the 50 areas in the adjacent rows, each row of areas having top and bottom aligned edges which define fold lines along which the sheet may be folded to bring a part of one row of surfaced areas into overlapping relation with 55 respect to a part of an adjacent row of surfaced areas.

In testimony whereof, I have hereunto set my hand, this 6th day of September, 1921.

LOUIS MEARS FORD.
